Invention

John A. McNeal

UNITED STATES PATENT OFFICE.

JOHN A. MCNEAL, OF MONTGOMERY COUNTY, MARYLAND.

CLAMP FOR PLOW-BEAMS.

SPECIFICATION forming part of Letters Patent No. 253,407, dated February 7, 1882.

Application filed December 20, 1881. (No model.)

To all whom it may concern:

Be it known that I, JOHN A. MCNEAL, a citizen of the United States, residing in the county of Montgomery and State of Maryland, have 5 invented a new and useful Clamp for Plow-Beams, of which the following is a specification.

My invention relates more especially to that class of plows having wooden beams, and has for its object the strengthening of the beam 10 against undue strain when used in rough ground or when heavy plowing is to be done, thus allowing a lighter or weaker beam, or one of softer wood, to be used when desired. I 15 attain this object by the mechanism illustrated in the accompanying drawings, in which—

Figure 1 is a side view of the plow-beam with one form of the strengthening-clamp applied. Fig. 2 is a bottom view of the same. Figs. 3 and 4 are enlarged views of the cross-bars. Figs. 5 and 6 show the clamp formed of an entire rod, running the whole length of the beam on both sides. Figs. 7 and 8 show 20 the same form of clamp applied to a plow having lugs or bearings formed on the standard 25 to receive the rod.

Similar letters refer to similar parts throughout the several views.

A represents an ordinary wooden plow-beam; B, a clevis; and C, Figs. 7 and 8, a standard. 30 D is a plate applied to the front end of the beam and grooved to receive the front loop or portion, E, of the clamp, the rear portion, E', being also held to the beam by a grooved plate, F, having spurs F' or other suitable securing devices.

G G' are bars resting against the under side of the beam for the rod of the clamp to bear against when under strain. Fig. 4 shows the bar G' enlarged, with notches or bearings for 40 the rods.

H H' are cross-bars, into which the ends of the rod may be passed, as in Fig. 3; or the bars may be perforated with a hole at each end for the passage of the rods; or two pieces may be bolted or clamped to make one solid perforated bar; or the rods may be secured in place in any other convenient way.

I is a screw-rod swiveled in one of the cross-bars, its threaded end engaging with the other, 45 the angular head or block I' serving to turn the

screw-rod by means of a wrench or otherwise. The rod may be flattened for that purpose, or any other convenient means may be employed to secure a grip or leverage.

I", Figs. 5, 6, 7, and 8, shows the tightening-screw and bar at the rear end of the beam; and E", a continuous straining-rod, running both sides of the beam, in which case one or more cross-bars are employed, as at G" G'", Figs. 5 and 6.

In case the plow is manufactured with a view to use the clamp, lugs or bearings, as at K K, Figs. 7 and 8, are formed upon the standard to receive the strain of the rods instead of the cross-bars.

Either form of clamp herein shown may be used, according to the kind of plow to which it is to be applied; and it is evident that various changes may be made in detail without affecting the scope of my invention.

In operation my strengthening-clamp is intended to be used upon old half-worn plows as well as upon new, and it is not intended to interfere with the ordinary attachments of the plow. For example, the re-enforcing plate D (when the clamp is not applied to the bare wood) is fitted upon the end of the beam, either with flanges, as at L L', Figs. 1 and 5, or with teats or spurs, as at L", Fig. 7, and, being of the same size as the beam, the clevis passes over it readily. Plates may also be applied to the rear end of the beam. The standard, the colter, and the gage-wheel attachment will not be interfered with in the application of the clamp as described. In case the beam is attached by a mortise to the handle, or in any of the ordinary ways, the long bent rod E", as seen in Figs. 5, 6, 7, and 8, passes outside of everything, and is strained by a bar and screw on the end of the beam; or the bar may be placed above the projecting portion of the beam against the handle; or the rod may pass above and over the beam, as at F, Fig. 1, and the plate at F may be strained from the end of the beam by means of a threaded extension or rod and nut, or by other convenient means.

Having described my invention, what I claim, and desire to secure by Letters Patent, is—

1. A strengthening-clamp for plow-beams, constructed substantially as described, com- 100

- bining a straining-rod, a tightening device, and bearings for the rod, and adapted to be applied to and removed from the plow-beam, as set forth.
5. 2. The combination, with a plow-beam, of a strengthening-clamp composed of a straining-rod, a tightening device, and bearings for the rod, substantially as described, whereby the beam may be re-enforced temporarily or permanently, as desired, without interfering with the standard or attachments of the plow.
3. The combination, with the plow-beam, straining-rod, tightening device, and bearings, of a grooved metallic plate or plates applied 15 at or near the end of the beam, substantially as described.
4. A strengthening-clamp for plow-beams, composed of a **U**-shaped straining-rod adapted to run each side of the plow-beam, a tightening device, and bearings for the rod, substantially as described.
5. In a clamp for strengthening a plow-beam, the combination of a **U**-shaped straining-rod, a tightening-screw or its equivalent, bearings for the rod, and bearing-plates at or near the 25 ends of the beam, substantially as described.

JOHN A. McNEAL.
